UNITED STATES PATENT OFFICE.

AARON F. BOYLAN AND ELZIE C. CHAMBERLIN, OF DENISON, IOWA.

FINGER-RING EXPANDER.

No. 827,290.

Specification of Letters Patent.

Patented July 31, 1906.

Application filed April 22, 1905. Serial No. 256,945.

To all whom it may concern:

Be it known that we, AARON F. BOYLAN and ELZIE C. CHAMBERLIN, citizens of the United States, residing at Denison, in the 5 county of Crawford and State of Iowa, have invented a new and useful Finger-Ring Expander, of which the following is a specification.

This invention relates to a finger-ring expander.

The object of the invention is to provide a simple, cheap, efficient, and novel implement which may be manipulated to effect expanding of rings, especially set-rings, without any 15 danger of injury to the stones and in which the operation of expanding is not attended with any marring of the ring, so that expensive refinishing when the expanding operation is completed is entirely obviated.

With the above and other objects in view, as will appear as the nature of the invention is better understood, the same consists in the novel construction and combination of parts 20 of a finger-ring expander, as will be hereinafter fully described and claimed.

In the accompanying drawings, forming a part of this specification, and in which like characters of reference indicate corresponding parts, Figure 1 is a view in perspective of 25 the implement, showing it operatively combined with a ring to be expanded. Fig. 2 is a view in transverse section on an enlarged scale. Fig. 3 is a side view of the open head.

The implement embodies a pair of levers 1 and 2, suitably connected for rocking movements relatively to each other by means of a stud 3, projecting from one end of one of the levers—in this instance the lever 2—and engaging a recess 4 in one end of the other lever, a pin 5 passing through the lever 1 and through one of a series of orifices 6 in the stud 3, serving to hold the parts connected. The lever 2 in this instance will be stationary, and the lever 1 will be fulcrumed by the pin 5 and moved relatively to the first-named lever. In order to effect the requisite adjustment of the lever 1 to cause the implement to perform its function, the stud 3 is provided with the series of orifices 6 referred to, thereby to 40 render the implement adaptable upon any size ring.

The lever 1 is provided with a head 7, in the end of which the recess 4 is located, and secured to the under side of the head or 45 formed integral therewith is a yoke 8, (more

clearly shown in Fig. 2,) between the members of which is mounted the expanding-roller 9, the same being held combined with the yoke by means of a removable pin 10. As usual, the roller will have its periphery 60 furnished with a groove of a shape to correspond with the exterior of a ring, and there will be a series of these rollers supplied with each implement in order to adapt it for use in connection with any kind of ring. The 65 end of the lever 2 which carries the stud 3 is provided with an open head 11, provided on its upper face with transversely-alined recesses or depressions 12, in which is adapted to rest a mandrel 13, upon which the ring R 70 to be expanded is placed. The recesses or seats in the head 11 will be of different depths to correspond to the taper of the mandrel, so that when the latter is positioned in the seats it will have a firm and solid bearing therein 75 and be held from any rocking movements. The seats, however, permit the mandrel to be rotated therein. By the provision of the open head a set-ring may be operated upon without the set coming in contact with any 80 part of the implement.

In the use of the implement a roller having the appropriate shape to coact with the ring is first selected and positioned in the yoke. The ring is then forced upon the mandrel as 85 far down as possible. The latter is then positioned upon the head 11, and the pin 5 is brought into the appropriate orifice in the stud 3 to cause the opposed faces of the two heads 7 and 11 to be in parallelism. Pressure is then applied to the levers, and upon a 90 rotary motion being imparted to the implement the expanding-roller will spread the ring. During the operation of the expanding care must be taken to see that the ring is 95 kept tightly associated with the mandrel; otherwise the proper expanding cannot be secured, and, furthermore, the circular form of the ring will be destroyed.

The implement of the present invention, while exceedingly simple of construction, will be found thoroughly effective in use for the purposes designed, may be cheaply and readily manufactured, and will secure the results designed as effectively as can be done by 105 higher-priced machines now on the market for this purpose.

Having thus described the invention, what is claimed is—

A ring-expander comprising a lever pro- 110

vided with an open head having transverse seats of different depths and with a stud provided with a plurality of orifices, a second lever detachably fulcrumed to the stud and carrying a depending yoke, and an expanding-roller mounted between the yoke members.

5 In testimony that we claim the foregoing

as our own we have hereto affixed our signatures in the presence of two witnesses.

AARON F. BOYLAN.
ELZIE C. CHAMBERLIN.
